UNITED STATES PATENT OFFICE.

HEBER ALLEN, OF BLOUNT, ILLINOIS.

FENCE.

SPECIFICATION forming part of Letters Patent No. 751,600, dated February 9, 1904.

Application filed November 3, 1903. Serial No. 179,655. (No model.)

To all whom it may concern:

Be it known that I, HEBER ALLEN, a citizen of the United States, residing at Blount, in the county of Vermilion, State of Illinois, have invented certain new and useful Improvements 5 in the Construction of Fences, of which the following is a full, complete, and exact description.

This invention relates to the construction of 10 fences, and especially to that type comprising a series of uprights or standards linked together by longitudinally-extending connections therebetween.

The object of the invention is the production 15 of a fence of the character described in which a minimum amount of wood will be employed in its construction and in which no portion of the wood so employed will be embedded in the ground, thus obviating the possible 20 rotting of same from contact with the earth.

Another object of the invention is to provide 25 a construction whereby the structural firmness of the uprights or standards will be increased in proportion to the increased lateral tension on the connecting-links therebetween.

With the above and other objects in view 30 the invention consists in the details of construction and in the arrangement and combination of parts to be hereinafter more fully described and claimed.

In describing the invention in detail reference will be had to the accompanying drawings, 35 forming part of this specification, and wherein like characters of reference denote corresponding parts in the several views, in which—

Figure 1 is a perspective view of a fence embodying my improved construction. Fig. 2 40 is a side elevation of one of the intermediate standards. Fig. 3 is a side elevation of one of the corner-posts.

Referring to the drawings, A represents the 45 intermediate uprights or standards, and B the corner-posts, employed in the construction of my improved fence. As shown, the intermediate standards A have flexible connections C and D extending, respectively, from the top

and base of the standard and secured to an anchor E in any suitable manner. The connections and anchor are fixed on the opposite sides of each successive standard. The posts B have similar connections and anchors fixed on two adjacent sides thereof. Flexible connections F, preferably of stout wire, serve to link the standards together, said connection passing around the opposite side of each successive standard, so as to exert a pull on the standard against its anchor when the tension 60 of the connecting-links is increased. The connecting-links F pass through suitable eyes G, secured to the standards. By providing the corner-posts B with anchors on adjacent sides it will be obvious that the structural firmness 65 of said posts is effected by the simultaneous tension of the connections F in different directions.

Having described my invention, what I claim as new, and desire to secure by Letters 70 Patent, is—

1. In a fence, the combination of a pair of corner-posts loosely anchored from adjacent faces thereof, a series of intermediate posts each successively and loosely anchored from 75 opposite sides and a series of flexible links connecting said posts, said links successively engaging the sides of said posts from which they are anchored.

2. In a fence, the combination of a pair of corner-posts loosely anchored from adjacent faces thereof, a series of intermediate posts, anchors situated on the opposite sides of each successive intermediate post, connections from the top and base of each post loosely securing 85 same to its respective anchor and a series of flexible connections or links connecting said posts, said links successively engaging the sides of said posts from which they are anchored. 90

In testimony whereof I have signed my name to this specification in presence of two witnesses.

HEBER ALLEN.
